UNITED STATES PATENT OFFICE.

JAMES H. REED, OF LYNN, MASSACHUSETTS, ASSIGNOR TO THE GLOBE
BUTTON-HOLE MACHINE COMPANY, OF KITTERY, MAINE.

METHOD OF BARRING BUTTON-HOLES.

SPECIFICATION forming part of Letters Patent No. 378,218, dated February 21, 1888.

Application filed May 9, 1887. Serial No. 237,534. (No model.)

To all whom it may concern:

Be it known that I, JAMES H. REED, of Lynn, in the county of Essex and State of Massachusetts, a citizen of the United States, 5 have invented a new and useful Method of Barring Button-Holes, of which the following is a full, clear, and exact description, reference being had to the accompanying drawings, forming a part of this specification, in explaining its nature.

The invention relates to a method of barring button-holes, which embraces the sewing or stitching of the bar by stitches which extend entirely across the end of the button-hole slit, 15 are in line therewith, and which are preferably of a length equal to about twice that of the stitch overlying the side and eye of the button-hole, and the completion or fastening of the end of the thread used in forming the bar- 20 ring-stitch by sewing one, two, or three additional stitches of substantially the length of the stitch used in sewing the button-hole itself, so that the barring-stitches are locked or fastened in place, and under such tension as may 25 be necessary for doing good work.

Referring to the drawings, Figures 1, 2, and 3 illustrate button-holes in different stages of completion, and Fig. 4 a portion of a completed button-hole.

30 The mechanism employed for carrying out the method herein described forms no part of this invention and need not be described, it being sufficient to briefly state that two threads are used and two needles and appropriate looping devices, one of which is above 35 the work-plate and the other below.

In the drawings, A indicates the upper needle, which is moved or reciprocated continuously in the same line or path, and A' is the 40 lower needle.

In stitching the sides and eye of a button-hole these needles have a fixed relation to each other—that is, each is reciprocated or moved upon a given line or track, which line 45 or track is not varied in any respect in relation to the line or track of the other. At the completion of the last side of the button-hole to form the longer stitch necessary for barring the end of the button-hole, and also to form a 50 stitch which shall be substantially twice the

length of the stitch which is used upon the sides and eye of the button-hole, one needle is moved automatically from the path in which it was reciprocated, or moved away from the other needle, to a position about twice as far 55 from it as that which it occupied during the stitching of the sides and eye, and it continues to move or reciprocate in this new position or upon this new line. This makes the length of the horizontal portion of the stitch twice 60 that which was before sewed by the same needles, and the needles are moved or reciprocated in their new relation to each other, and the looping devices operated to carry the upper and lower threads and spread the loops 65 until any desired number of these long stitches have been made across the end of the button-hole. At the completion of the last long stitch the movable needle is moved back to its original position, and one, two, or more stitches 70 sewed through the material to fasten the ends of the threads.

Having thus fully described my invention, I claim and desire to secure by Letters Patent of the United States—

The method of barring button-holes with two threads herein described, comprising the forming of holes in the material in which the button-hole is formed, one upon each side of the button-hole slit at the end opposite the 80 eye, passing the bight of one thread through one of the holes, opening its loop upon the under side of the material, and passing the bight of the second thread through said loop and the other hole, and opening the bight 85 above the material to form a loop for the reception of the bight of the first-named thread in the formation of the second stitch, so forming two or more stitches of a length twice or substantially twice that of the length of the 90 stitch of the edge of the button-hole, and then forming a shorter locking-stitch by forming two holes closer to each other than those first named and passing the bights of the two threads through the holes and opened loops, 95 as specified, as and for the purposes set forth.

JAMES H. REED.
